UNITED STATES PATENT OFFICE.

ROBERT S. KIRKPATRICK, OF DES MOINES, IOWA, ASSIGNOR TO ELMER HICKS, OF DES MOINES, IOWA.

SANITARY WATERING-TROUGH.

1,319,095.

Specification of Letters Patent. Patented Oct. 21, 1919.

Application filed March 17, 1917. Serial No. 155,526.

To all whom it may concern:

Be it known that I, ROBERT S. KIRKPATRICK, citizen of the United States of America, and resident of Des Moines, Polk county, Iowa, have invented a new and useful Sanitary Watering-Trough, of which the following is a specification.

The object of this invention is to provide an improved construction for a sanitary, self-feeding watering trough for poultry or animals.

A further object of this invention is to provide improved means for removably mounting a trough in a shell and relative to the water tank.

My invention consists in the construction, arrangement and combination of elements hereinafter set forth, pointed out in my claim and illustrated by the accompanying drawing, in which—

Figure 1 is a side elevation of my improved device, dotted lines indicating the trough in partially removed position. Fig. 2 is a cross-section on the line 2—2 of Fig. 1, the door being closed. Fig. 3 is a plan of the trough. Fig. 4 is a vertical section on the line 4—4 of Fig. 3. Fig. 5 is a detail vertical section of the valve and valve regulating devices.

Fig. 6 is a vertical front to rear sectional view through the trough;

Fig. 7 is a vertical sectional view taken in a plane at right angles to the plane of Fig. 6 and looking in the direction of the forward side of the trough;

Fig. 8 is a view similar to Fig. 7 but looking in a direction toward the rear side of the trough.

In the construction of the device as shown the numeral 10 designates a shell, preferably of cylindrical form and constructed of sheet metal, formed with an opening near its bottom closable by a door 11 slidably mounted in vertical slide bearings 12 at the sides of said opening, the door being provided with a handle or knob 13. A water tank 14 is mounted in the upper portion of the shell 10, preferably being of smaller diameter than said shell so that it is spaced therefrom, leaving an annular, or partially annular opening between the two members. The top of the shell 10 is rigidly fixed to the side walls thereof and is generally convex, with an opening in its central portion normally

closed by a tight fitting cap 15. The top of 55 the water tank 14 is formed concave in its central portion below the opening of the top of the shell, and has in its central portion an opening, leading to the interior of the said tank, which opening normally is 60 closed by a screw cap 16, (dotted lines Fig. 1). Thus a funnel shaped opening to the water tank is provided, through which water may be poured or otherwise introduced, said funnel entrance normally being covered 65 and protected against dirt and the like by the cap 15. The screw cap 16 also seals the water tank to air-tight condition when in place.

Drink openings 17, 18 are formed in the 70 shell 10 at diametrically opposed points, and a trough 19, preferably semi-circular in cross-section, is removably and replaceably mounted across said shell with its ends beneath said drink openings, the top of said 75 trough being spaced slightly below the bottom of the water tank 14. An opening 17', is formed in the shell 10 below and as a continuation of the drink opening 17, for the trough 19, and when said trough is in position its outer end wall 19' closes said opening 17, 17' and forms practically a continuation of the side wall of the shell. Spaced flanges 20, 21 are formed on and extend downwardly from the bottom of the water 80 tank 14, extending across from the drink opening 17 to the drink opening 18, and said flanges are turned inwardly at their lower margins to provide horizontal guide bearings for the side margins of the trough 19, 90 which is formed with inturned flanges 22, 23 on the side margins of its top to slide beneath the first mentioned flanges. A semi-circular shelf 24 preferably is provided on the inner side of the shell 10 beneath the 95 drink opening 18, to engage and support the inner end of the trough 19 when in place. The trough 19 also preferably is formed with inwardly projecting lugs or hooks 25, at opposite sides of the top of its outer end, 100 to engage over the outer ends of the flanges 20, 21 when the trough is pushed into position. The trough 19, in addition to being semi-circular in cross-section, also preferably is provided with sloping abutments 26 105 at its ends, merging into the curves of the sides of the trough, so that no corners are left for lodgment of filth and other unsani-

tary substances, and making the trough easy to clean and keep in sanitary condition.

A feed pipe 27 is fixed to the bottom of the water tank 14 and communicates with the interior thereof, and projects downwardly within the trough 19 when in position. The feed pipe 27 projects materially below the plane of the top of the trough 19 and automatically maintains the level of the water in said trough at the desired point, it being remembered that the top of the water tank is not open to the atmosphere. Means is provided for closing the feed pipe 27 to permit removal of the trough 19, and for this purpose I have shown a flat valve 28 overlying the upper end of the pipe 27, within the tank 14 and adapted to close said upper end of said pipe. The valve 28 is adapted to be engaged by a stem 29 extending downwardly through the pipe 27, passing through a slide bearing 30 within and fixed to said pipe, and pivoted at its lower end to a lever 31 extending transversely below the lower end of said pipe and fulcrumed at one end on a bracket 32 projecting laterally from the lower end of said pipe. The fulcrumed end of the lever 31 is pinched tightly to the bracket 32 by the pivoting rivet 33, so that said lever is frictionally held and will remain in whatever position it is placed manually. Normally the lever 31, valve stem 29 and valve 28 are positioned as shown with the valve raised or in open position, so that water in the tank 14 may feed automatically to the trough 19 through the pipe 27 to replace water as it is used from said trough; but when it is desired to remove the trough from its place in the device, for cleaning or other purpose, the free end of the lever 31 is moved downwardly so that the valve 28 may seat against the upper end of the pipe and prevent flow of water thereto.

A lamp 34 or other heating device may be mounted loosely in the lower part of the shell 10, beneath the trough 19 and tank 14, and be employed in cold weather to prevent freezing of the water in said devices.

A supply pipe 35 leads from a source of water supply (not shown), enters the lower part of the shell 10, and is provided with a cut-off valve 36. A hose 37 may be attached to the pipe 35 and be employed at times to convey water from said pipe to the tank 14 by inserting the free end of said hose in the opening at the top of said tank, by removing the caps 15 and 16, said hose being led out through the opening in said shell, and being

folded in the lower part of the shell when not in use for this purpose.

To remove the trough 19 from its seat in the shell, draft is first applied to slide it outwardly until its hooks disengage the flanges and its inner end is clear of the shelf 24, then its outer end is dropped into the extension opening 17' and simultaneously the inner end will drop to a position where it may pass beneath the pipe 27 and lever 31. A decided advantage is to be found in the removability and replaceability of the trough 19, so that it may be kept at all times in sanitary condition. I prefer to provide the troughs 19 in duplicate for each watering device, so that one may be subjected to a thorough cleaning, airing and sunning while the other is in use.

Vents 38 are provided in the upper part of the shell 10 and communicating with the space between said shell and the tank 14, to permit circulation of heated air around said tank, and permit the escape of products of combustion.

If desired the tank may be filled by pouring from a vessel into the concavity at the top of the tank, through the opening closable by the cap 15, the water entering the tank through the opening normally closed by the screw cap 16. The use of the tight fitting cap 15 in the top of the shell prevents the entrance of dirt and the like to the funnel of the tank, and insures the injection of clean water to the tank without becoming defiled in the operation of its introduction thereto, as would be the case were the said funnel exposed at all times.

I claim as my invention:—

In a device of the class described, the combination with a shell provided at diametrically opposite points in its wall with drain openings, one being extended lower than the other, an internal shelf fixed beneath the higher opening, a reservoir within the upper portion of the shell, and flanges pendant from the reservoir and having guides aligned with the upper portions of said openings; of a trough removably disposed within the shell and closed at its ends, its rear end adapted to rest on said shelf and its front end having a wall at this time closing said extension opening, flanges along the sides of the trough underlying said guides, and hooks at the front ends of the flanges engaging over said guides when the trough is in place.

Signed by me at Des Moines, Iowa, this eleventh day of March, 1916.

ROBERT S. KIRKPATRICK.
